(57) **CLAIM**

The ornamental design for a data storage device holder as shown and described.

DESCRIPTION

FIG. 1 is a rear-right perspective view of a data storage device holder of a first embodiment in a closed position. FIG. 2 is a top view of the data storage device holder of the first embodiment in the closed position.

FIG. 3 is a bottom view of the data storage device holder of the first embodiment in the closed position.

FIG. 4 is a left-side view of the data storage device holder of the first embodiment in the closed position.

FIG. 5 is a right-side view of the data storage device holder of the first embodiment in the closed position.

FIG. 6 is a front view of the data storage device holder of the first embodiment in the closed position.

FIG. 7 is a rear view of the data storage device holder of the first embodiment in the closed position.

FIG. 8 is a rear-right perspective view of the data storage device holder of the first embodiment in an open position. FIG. 9 is a top view of the data storage device holder of the first embodiment in the open position.

FIG. 10 is a bottom view of the data storage device holder of the first embodiment in the open position.

FIG. 11 is a left-side view of the data storage device holder of the first embodiment in the open position.

FIG. 12 is a right-side view of the data storage device holder of the first embodiment in the open position.

FIG. 13 is a front view of the data storage device holder of the first embodiment in the open position.

FIG. 14 is a rear view of the data storage device holder of the first embodiment in the open position.

FIG. 15 is a rear-right perspective view of a data storage device holder of a second embodiment in an open position.

FIG. 16 is a top view of the data storage device holder of the second embodiment in the open position.

FIG. 17 is a bottom view of the data storage device holder of the second embodiment in the open position.

(Continued)

FIG. 18 is a left-side view of the data storage device holder of the second embodiment in the open position.

FIG. 19 is a right-side view of the data storage device holder of the second embodiment in the open position.

FIG. 20 is a front view of the data storage device holder of the second embodiment in the open position; and,

FIG. 21 is a rear view of the data storage device holder of the second embodiment in the open position.
